COMBINED FILTER AND REGULATOR FOR PRESSURIZED FLUID

Clair Dean Holben and John Joseph Humphrey, Denver, Colo., assignors to C. A. Norgren Co., Littleton, Colo.

Filed July 17, 1972, Ser. No. 272,162

Term of patent 14 years

Int. Cl. D23—01

U.S. Cl. D23—4

FIG. 1 is a perspective view of a combined filter and regulator for pressurized fluid showing our new design; FIG. 2 is a side elevational view thereof; FIG. 3 is an additional side elevational view thereof; FIG. 4 is a top view thereof; and FIG. 5 is a bottom view thereof.

We claim:

The ornamental design for a combined filter and regulator for pressurized fluid, as shown.
